UNITED STATES PATENT OFFICE.

HERBERT S. JANDUS AND JOHN RICHARD MORGAN, OF DETROIT, MICHIGAN, ASSIGNORS TO THE C. G. SPRING & BUMPER COMPANY, OF DETROIT, MICHIGAN, A CORPORATION OF DELAWARE.

DESIGN FOR A VEHICLE BUMPER.

Application filed December 21, 1927. Serial No. 24,578. Term of patent 14 years.

To all whom it may concern:

Be it known that we, HERBERT S. JANDUS and JOHN RICHARD MORGAN, citizens of the United States, residing at Detroit, in the county of Wayne and State of Michigan, have invented a new, original, and ornamental Design for a Vehicle Bumper, of which the following is a specification, reference being had to the accompanying drawing, forming part hereof, wherein

Fig. 1 represents a plan view and Fig. 2 represents a front elevation of a vehicle bumper exhibiting our new design.

We claim:

The ornamental design for a vehicle bumper substantially as shown.

HERBERT S. JANDUS.
JOHN RICHARD MORGAN.
